LIQUID DISPENSING CONTAINER FOR MILK OR THE LIKE

David D. Tompkins, Worthington, Ohio, assignor to The Corrugated Container Company, Columbus, Ohio, a corporation of Ohio

Filed Feb. 13, 1967, Ser. No. 5,791

Term of patent 14 years

(Cl. D94—3)

FIGURE 1 is a perspective view of a liquid dispensing container for milk or the like, showing my new design; FIGURE 2 is a bottom view of the container; and

The essential features of the design reside in the solid line portions of the drawings.

I claim:

The ornamental design for a liquid dispensing container for milk or the like, substantially as shown and described.
